(57) **CLAIM**

The ornamental design for an electrical contactor for low voltage switching devices, as shown and described.

DESCRIPTION

FIG. 1 is a front elevation view of an electrical contactor for low voltage switching devices showing our new design;
FIG. 2 is a rear view elevation thereof;
FIG. 3 is a top plan view thereof;
FIG. 4 is a bottom plan view thereof;
FIG. 5 is a left side elevation view thereof;
FIG. 6 is a right side elevation view thereof; and,
FIG. 7 is a perspective view thereof.
